United States Patent Office

Des. 222,023

Patented Sept. 21, 1971

222,023

RACKET

Peter A. Latham, Newburyport, and Paul E. Brefka,
Southboro, Mass. (both of 39 Commercial Wharf, Bos-
ton, Mass. 02110)

Filed Oct. 8, 1970, Ser. No. 25,393

Term of patent 14 years

Int. Cl. D21—02

U.S. Cl. D34—5

FIG. 1 is a perspective view of a racket showing our new design;

FIG. 2 is a plan view thereof;

FIG. 3 is a side view thereof;

FIG. 4 is a top view thereof; and

FIG. 5 is a bottom view thereof.

We claim:

The ornamental design for a racket, as shown.
